(57) **CLAIM**

We claim the ornamental design for a tamper proof label, as shown and described.

DESCRIPTION

FIG. 1 is an isometric view in elevation of a container and cap assembly having the tamper proof label of the present invention affixed thereto;

FIG. 2 is a front view in elevation of a container and cap assembly having the tamper proof label of the present invention affixed thereto;

FIG. 3 is a side view in elevation of a container and cap assembly having the tamper proof label of the present invention affixed thereto;

FIG. 4 is a front view in elevation of the tamper proof label of the present invention;

FIG. 5 is a back view in elevation of the tamper proof label of the present invention;

FIG. 6 is a top view in elevation of the tamper proof label of the present invention; and,

FIG. 7 is a bottom view in elevation of the tamper proof label of the present invention.

The label is characterized as having upper and lower portions, the upper portion being further characterized as 2 opposing tabs. The upper and lower portions being joined together by a tear strip having perforations, wherein pull tabs are located at opposite ends of the strip.

The broken line shown on the label represents perforation. The broken line showing of a container and cap assembly is for illustrative purposes only and forms no part of the claimed design.
